UNITED STATES PATENT OFFICE.

EDWARD WESTON, OF NEWARK, NEW JERSEY, ASSIGNOR TO THE UNITED STATES ELECTRIC LIGHTING COMPANY, OF NEW YORK, N. Y.

DYNAMO-ELECTRIC MACHINE.

SPECIFICATION forming part of Letters Patent No. 301,027, dated June 24, 1884.

Application filed December 29, 1883. (No model.)

To all whom it may concern:

Be it known that I, EDWARD WESTON, a subject of the Queen of Great Britain, and a resident of Newark, in the county of Essex and 5 State of New Jersey, have invented certain new and useful Improvements in Dynamo-Electric Machines, of which the following is a specification, reference being had to the drawing accompanying and forming a part of the 10 same.

My invention relates to systems of generating and distributing electrical currents, in which the devices for utilizing the current are included in multiple arc or derivation to the 15 main conductors from the source of supply. In the system developed and used by me the dynamo-electric machines or generators are constructed in such manner that they develop an electro-motive force that is constant for all 20 variations of resistance in the external circuit within the normal working limits of the machine. The construction of such machines has been described by me in a former patent, No. 278,641, and to such machines of that class 25 as have their field-circuit in derivation to the main or armature circuits my present invention pertains. The development of a constant electro-motive force, however, by such machines presupposes a uniform rate of rotation 30 of the armature; but it may be often necessary to run such machines by an engine of variable speed, in which case the electro-motive force varies. This is primarily due to two causes: first, supposing the speed to increase, to the 35 greater number of lines of force traversed in a given time by the armature-conductors; secondly, to the increased flow of current through the field-magnet coils and the greater magnetic intensity of the field. The converse of this 40 occurs on diminution of the speed.

The object of my invention is to prevent, as far as practicable, these variations by maintaining the magnetism of the field constant; and this I effect by combining with the derived field-circuit an automatic rheostat of 45 any kind, which, by varying the resistance of the field-circuit, maintains through the same a uniform flow of current.

This invention is illustrated in the accompanying diagram of the system.

A is a dynamo-electric machine constructed

for developing a constant electro-motive force, as above set forth, and having a derived field-circuit, B.

C C are the main conductors from the commutator; D, the cross-circuits, and E the incandescent lamps or similar devices included therein.

F is an electro-magnet, or its equivalent, such as a helix and core; G, a series of contact-plates; H, a series of resistance-coils connected therewith in the ordinary way.

K is a pivoted contact-arm connected to the core or armature L of the magnet. The coils of the magnet or helix are included in the derived field-circuit. The rheostat is set or adjusted to include a certain resistance in the field-circuit during the normal running of the machine. If, for any cause, the speed of the machine should increase, the tendency of a stronger current to flow through the field-circuit is checked by the operation of the rheostat, which inserts a greater resistance in the circuit. The converse of this takes place upon a diminution of the speed. In this way the magnetism of the field is preserved uniform, so that the ordinary variations of the speed of rotation of the armature—such as are likely to occur in practice—produce slight variations in the electro-motive force developed by the machine.

While the variations in the resistance of the field-circuit might be effected by other means than that shown, I prefer the system illustrated as being the most simple and effective.

I am aware that a variable resistance has been included in the field-circuit of machines, and such I do not claim, broadly; but

What I claim is—

The combination, with a dynamo-electric machine having a field-circuit derived from the main or armature circuit, of a variable resistance and electro-magnet for operating the same, both included in the field-circuit, as and for the purpose specified.

In testimony whereof I have hereunto set my hand this 23d day of November, 1883.

EDWARD WESTON.
